CUPOLA

Joseph R. Parsons, Chicago, Ill., assignor to
United States Gypsum Company, Chicago, Ill.,
a corporation of Illinois

Application June 10, 1940, Serial No. 339,595
In Canada April 15, 1940

4 Claims. (CL. 266—38)

This invention relates to a cupola, and has for its primary object the provision of a new and improved cupola and discharge-means for producing a substantially steady flow of a melt from which rock wool, mineral wool, or glass wool may be formed.

Cupolas have long been employed as means for melting metals and mineral substances. They have not proven entirely satisfactory for all purposes, however, particularly when the cupola is used for melting mineral material used for the production of mineral wool. The standard practice in cupola operation is to extract the melt from the side of the cupola at a point near the bottom. The undesirable results of this practice have been at least two-fold. In the first place, the melt accumulating in the bottom of the cupola remains in contact with the fuel undergoing combustion and has a tendency to absorb excessive amounts of carbon from the fuel bed. This is particularly undesirable when the cupola is used to produce a mineral melt which is blown to a mineral wool product, because the product is undesirably darkened by the carbon. Secondly, the path of flow of the melt from a hole positioned in the side of the cupola is usually longer than desirable and the melt is chilled to an excessive degree, particularly if the melt must pass through water-cooled side walls of the cupola. An outlet formed in the side walls of the cupola also may result in a variable flow of melt, since the flow may be diminished or even stopped if it should chill within the spout. Under such circumstances, it is necessary to increase the temperature of the melt, which is also undesirable, since increased heat in the melt increases its capacity to absorb carbon from the fuel bed.

It is, therefore, one object of the present invention to provide a cupola in which the above-indicated undesirable features have been eliminated. In accordance with this invention, a cupola is provided in which the melt is removed from the cupola substantially as soon as it is formed. The amount of carbon which it absorbs from the combustion chamber is, therefore, markedly reduced.

The present invention has for a further object the provision of a cupola which has a tap hole or tap holes through which the rate of discharge of the melt from the cupola may be adjusted and uniformly controlled. The tap holes are so constructed that the melt passing therethrough does not have a tendency to chill, and therefore a constant flow of melt from the cupola is insured.

Also, in accordance with this invention, means are provided for conveniently adjusting the rate of flow of melt from the cupola by changing the size of the outlet through which the melt passes from the cupola.

Further and additional objects of this invention will appear from the following description, the accompanying drawing, and the appended claims.

In accordance with one embodiment of this invention, a cupola is provided having a combustion chamber into which the material to be melted, fuel, and oxygen-containing gases are introduced, a tap hole positioned adjacent the bottom of the chamber for removing the melt substantially as rapidly as it is formed, and a movable tap hole plate positioned adjacent the bottom of the cupola, said plate having an orifice which registers with said tap hole for the purpose of controlling the amount of melt passing therethrough.

The tap hole plate positioned adjacent the bottom of the cupola is adjustable and may contain a plurality of orifices, each of which is adapted to be registered with a corresponding tap hole in the bottom of the cupola and each of which may be of a different size, so that any predetermined flow of melt may be obtained from the cupola. Furthermore, the rate of flow may be further regulated by partially closing off the passageway for the escaping melt by moving the tap hole plate to a slight degree so that the tap hole and plate orifice are no longer in full register. The amount of melt flowing through any one orifice, therefore, may be readily adjusted. The tap hole plate is so constructed that, when it is in the desired position, the amount of melt flowing through the orifice remains substantially constant, the melt does not solidify around it, and it is unnecessary for an operator to give the cupola and the flow therefrom continuous attention.

In accordance with a further embodiment of this invention, a cupola is provided which has a plurality of tap holes or openings positioned in the bottom thereof in order to effect a rapid removal of the melt from the cupola substantially as soon as it is formed. This rapid removal is desirable because of the tendency of the melt to absorb carbon from the fuel within the combustion chamber, whereby the melt becomes unduly darkened. The bottom of the cupola is provided with a number of tap holes, each of which is situated in the lowermost portion of one of a plurality of depressions posi-

tioned in the bottom of the cupola. Each of the depressions is separated from the others by means of a conduit positioned adjacent the bottom of the cupola, through which a cooling fluid may be passed. During the operation of the cupola, the cooling effect produced by the conduit causes a certain amount of slag to solidify adjacent thereto, thus building up a ridge portion between the depressions and permitting the molten material to flow out through the tap holes positioned in the lowermost portions thereof. If desired, tap hole plates with orifices, previously indicated and hereinafter more fully described, may be positioned adjacent each one of the tap holes for regulating the rate of flow of melt from each tap hole.

When the cupola is employed for melting mineral material for the production of mineral wool, the end of a blowpipe is positioned below the tap hole so that the melt falls into a high velocity stream of steam or air whereby the mineral wool is formed. A chamber is provided for collecting the resulting mineral wool fibers. In a mineral wool blowing apparatus having a cupola with a plurality of tap holes, a number of blowpipes are provided equal to the number of tap holes, whereby the melt from each of the holes is blown by each blowpipe into the mineral wool collecting chamber. It is preferable that the tap holes be staggered somewhat so that the blowpipes below the cupola may be positioned in the same plane and all blow the disintegrated melt stream in a single direction into a single mineral wool collecting chamber.

For a more complete understanding of this invention, reference will now be had to the drawing, in which:

Fig. 1 is a diagrammatic elevational view, taken partially in section, showing a cupola associated with a mineral wool blowing and collecting chamber constructed in accordance with one embodiment of this invention;

Fig. 2 is a bottom view of the cupola taken along the line 2—2 of Fig. 1;

Fig. 3 is a cross sectional view of the cupola taken along the line 3—3 of Fig. 1;

Fig. 4 is a plan view of a tap hole plate that may be used with a bottom discharge cupola constructed in accordance with one embodiment of this invention;

Fig. 5 is a cross sectional view of the tap hole plate taken along the line 5—5 of Fig. 4;

Fig. 6 is a detail view of the bottom portion of a modified form of cupola having two bottom discharge tap holes;

Fig. 7 is a cross sectional view of the modified cupola taken along the line 7—7 of Fig. 6;

Fig. 8 is similar to Fig. 7, but shows a cross sectional view of the bottom of a second modified form of cupola having four tap holes; and

Fig. 9 is an enlarged sectional view through one of the tap holes of the cupola.

Referring now more particularly to Figs. 1 through 5, a cupola is provided having an outer side wall 10 and an inner side wall 12 which co-operate to provide a cooling water jacket 14 completely surrounding the sides of the cupola. Cooling water for the water jacket is introduced at the lower end of the jacket through an inlet pipe 16 and is withdrawn at the top through an outlet pipe 18. As shown, the cupola is provided with an unjacketed sheet metal bottom portion 20 which may be protected from direct contact with the melt formed in the cupola by means of a layer of sand 22 or other refractory material.

In a central portion of the bottom of the cupola a tap hole 24 is provided whose edges are protected by a collar 26 of refractory material. The collar 26 prevents the melt from contacting the sheet metal bottom portion 20, and holds the sand in the layer 22 away from the tap hole 24.

On the under side of the bottom plate 20 adjacent the tap hole 24 is positioned a tap hole plate 28 slidably mounted on a pair of inwardly disposed L-shaped brackets 30 which may be secured to the bottom plate 20 in any desired manner. The tap hole plate 28 has one or more orifices 32 which are positionable by sliding the plate 28 on the brackets 30 to register with the tap hole 24. Suitable handles or engaging means 34 are provided on the tap hole plate 28 so that the tap hole plate may be engaged by a suitable tool to position the plate so that one or the other of the orifices may be brought into registry with the tap hole 24 in the bottom of the cupola or to move an orifice out of full registry with the tap hole whereby the rate of flow of melt from the bottom of the cupola is diminished to the desired extent. The flow of melt from the cupola thus may be regulated by providing a plurality of different size orifices in a single plate or by adjusting the relative positions of the orifice 32 and the tap hole 24 with respect to each other.

In accordance with one embodiment of this invention, as more particularly shown in Fig. 5, the orifice 32 in the tap hole plate 28 has a countersink 36 which is preferably on that surface of the plate away from the tap hole 24 when the plate is in position adjacent the bottom of the cupola. The tap hole plate 28 is thus somewhat thinner adjacent the orifice 32 and the melt keeps the metal surrounding the orifice 32 at a sufficiently high temperature to prevent the melt from solidifying adjacent the orifice. Consequently, the effective size of the orifice 32 remains substantially constant in diameter at all times and periodic cleaning of it to break out any solidified slag becomes unnecessary. The metal tap hole plate 28, however, is sufficiently thick so that a certain proportion of the heat imparted by the melt to the plate adjacent the orifice 32 is conducted away from the orifice and becomes dissipated. This is desirable because, if some means were not provided for dissipating this heat, the side walls of the orifice 32 have a tendency to melt, thus increasing the volume of melt flowing therethrough. The countersink 36 adjacent the orifice 32 is of such size and shape that it permits the metal adjacent the orifice to be maintained at a sufficient temperature to prevent the melt from solidifying in the orifice, but, on the other hand, permits a sufficient amount of heat to be conducted away from the side walls of the orifice, whereby melting of the plate is prevented.

It has been found that a suitable tap hole plate may comprise cast iron. However, any other material may be employed which will withstand the temperature to which the plate is heated during operation of the cupola. A cast iron plate having an orifice with a diameter of $\frac{3}{4}$ inch, 1 inch, or $1\frac{1}{4}$ inches may suitably be about 6 inches square and $\frac{1}{2}$ inch thick. The countersink for a 1-inch orifice may be about $2\frac{1}{4}$ inches in diameter adjacent one surface of the plate and have uniformly converging side walls extending into the plate and terminating about $\frac{1}{8}$ inch from the opposite surface of the plate, as indicated (on a reduced scale) in Figs. 4 and 5. It will, of course, be clear that the various dimen-

sions of the tap hole plate, the orifice, and the countersink may be varied in relation to each other within wide limits to produce the desired result, particularly when a plurality of orifices are provided in the plate as previously indicated.

The end of the blowpipe 38, positioned underneath the tap hole 24 and orifice registered therewith, blows a stream of steam or air at high velocity athwart the falling stream of melted material 49 to disintegrate the same, thereby forming the mineral wool 42 which is collected in a suitable settling chamber 44.

The fuel for producing the melt and material to be melted are introduced into the top of the cupola through an opening 46 which is opened and closed by a vertically movable plunger 48. As shown, a funnel-shaped structure 50 forms the top of the cupola and provides the side walls of a hopper into which may be placed the fuel and mineral material prior to the time that it is introduced into the cupola by depressing the plunger 48. The fuel and mineral material are introduced into the cupola through the opening 46 in the form of briquettes which may be formed by intimately mixing comminuted mineral matter and solid fuel with a binder and pressing the mixture, whereby the desired briquette is formed.

The oxygen-containing gases, such as air, for promoting combustion of the fuel in the cupola are forced into the cupola by means of an electrically motivated fan 54 through a conduit 55 and a wind box 56 which surrounds the lower side walls of the cupola. A plurality of apertures 58 provide passageways for the air from the wind box 56 to the inside of the cupola. The gaseous products of combustion escape through a suitable flue or chimney 60.

It is clear from the foregoing description that the fuel is ignited in the cupola, and the air introduced through the wind box 56 and the openings 58 promotes rapid combustion of the fuel to heat the interior of the cupola to temperatures sufficient to melt the mineral material compounded with the fuel in the briquettes 52. The melt thus formed flows to the bottom of the cupola out through the tap hole 24, through the orifice 32, and at a steady rate into the stream of rapidly moving steam or air discharged from the blowpipe, whereby the melt is drawn out into mineral wool fibers and projected into the settling chamber 44. The volume rate of discharge of the melt may be controlled by proper positioning of the tap hole plate as previously indicated.

Referring now more particularly to Figs. 6 and 7, a cupola is shown which contains a bottom portion having a pair of tap holes positioned in the lowermost portions of two depressions contained in the bottom of the cupola. The general construction of the bottom of the cupola, the tap holes, and the tap holes plates is similar to that previously described. However, the depressions between the tap holes are separated by a ridge through which passes a conduit 62, through which a cooling fluid such as water may be passed. The cooled conduit 62 has an amount of slag solidified around it, which slag forms a part of the ridge portion 64 between the two tap holes 24a and 24b. The ridge portion is permanent and does not have a tendency to corrode away, since the slag always provides a solidified portion adjacent the cooling conduit 62. The cooling conduit, however, does not exert such a great cooling effect on the melt being produced in the cupola as to affect its flowability through the tap holes in the bottom

of the cupola. Consequently, the fluidity of the melt is not impaired by the presence of the dividing cooling conduits 62, and a means has been provided for withdrawing a plurality of molten streams from a single cupola. A pair of blowpipes 38a and 38b are provided below the tap holes 24a and 24b for blowing the melt into a mineral wool chamber if such is desired.

Fig. 8 shows a construction in which the bottom 10 of a cupola is divided into four sections or depressions having a tap hole positioned in the lowermost portions of each and which depressions are separated one from the other by means of crossing cooling conduits 66 and 68 which have a function 15 similar to the conduit 62 previously described in connection with Figs. 6 and 7. The tap holes positioned in the bottom of the depressions of the cupola constructed in accordance with Fig. 8 are staggered somewhat so that the blowpipes 20 positioned below the tap holes lie in the same plane and are directed in the same direction so that all of the mineral wool formed thereby is directed into a single mineral wool collecting chamber.

25 It will be clear from the above description that a construction has been provided which has many desirable features not inherent in any of the devices of the prior art. While the cupolas specifically described above are those in which the melt 30 is formed directly within the combustion chamber of the cupola, other types of cupolas and melt forming furnaces are also included within the scope of this invention.

While several particular embodiments of this 35 invention are shown above, it will be understood, of course, that the invention is not to be limited thereto since many modifications may be made, and it is contemplated, therefore, by the appended claims, to cover any such modifications as fall 40 within the true spirit and scope of this invention.

I claim:

1. In a cupola for the manufacture of glass wool or the like and having a melting chamber for continuously forming melt therein and continuously discharging said melt at a high temperature through a tap hole in the bottom of said cupola, a tap plate positioned snugly under said tap hole and having a corresponding tap aperture through a relatively thin portion of said plate to form a thin edge wall around said aperture, said plate increasing in thickness outwardly and downwardly from said aperture to provide an obtuse-angle conical depression substantially on the axis of said aperture so that the said increasing thickness portion of said plate has a heat conducting capacity capable of maintaining said thin edge wall below its melting temperature but above a chilling temperature of the issuing melt.

2. In a cupola for the manufacture of glass 60 wool or the like comprising a melting chamber for continuously forming melt therein and continuously discharging said melt through a tap hole in the bottom of said cupola, the combination with a refractory lining for said tap hole, of a metal 65 tap plate positioned snugly under said lined tap hole for slidable registration therewith, said plate having a corresponding tap aperture through a relatively thin portion of said plate to form a thin edge wall around said aperture, said plate increasing in thickness outwardly and downwardly from said aperture to provide an obtuse-angle conical depression substantially on the axis of said aperture so that the said increasing thickness portion of said plate has a heat conducting capacity capable of maintaining said thin edge

wall below its melting temperature but above a chilling temperature of the issuing melt.

3. In a cupola of the character described having at least two spaced tap holes through the bottom wall thereof, a cooling conduit extending transversely between said holes closely adjacent the bottom of said cupola, a covering of sand or the like in the bottom of said cupola and forming a ridge or elongated mound over said pipe to direct melt to said tap holes, said cooling conduit being of sufficient cooling capacity to cause a layer of solidified slag to form at least a part of the ridge between said tap holes, and a relatively thick tap plate slidably supported under at least one of said tap holes snugly adjacent the bottom of said cupola and having a tap aperture movable into alignment with its associated tap hole, said plate being sufficiently thin at the edge of said aperture and closely adjacent thereto to prevent chilling and solidifying of the melt in and closely

5 adjacent said aperture, said plate gradually increasing in thickness downwardly and outwardly from said edge over a portion of its extent so that sufficient progressively increasing heat conductivity is provided outwardly from said edge to prevent melting said edge while simultaneously maintaining said edge at a temperature closely approaching the temperature of the melt.

10 4. In a cupola of the character described having at least two spaced tap holes through the bottom wall thereof, a cooling conduit extending transversely between said holes closely adjacent the bottom of said cupola, a covering of sand or the like in the bottom of said cupola and forming a ridge or elongated mound over said pipe to direct melt to said tap holes, said cooling conduit being of sufficient cooling capacity to cause a layer of solidified slag to form at least a part of the ridge between said tap holes.

15 JOSEPH R. PARSONS.
